(57) **CLAIM**

The ornamental design of a three wheel belt grinder, as shown and described.

DESCRIPTION

FIG. 1 is a perspective view taken from the front, top, right-hand side of a three wheel belt grinder on a base; FIG. 2 is a perspective view taken from the front, top, right-hand side of a three wheel belt grinder showing our new design;

FIG. 3 is a perspective view taken from the front, top, left-hand side thereof;

FIG. 4 is a perspective view taken from the back, bottom, left-hand side thereof;

FIG. 5 is a perspective view taken from the back, bottom, right-hand side thereof;

FIG. 6 is a front elevational view thereof;

FIG. 7 is a rear elevational view thereof;

FIG. 8 is a side elevational view of the right side thereof;

FIG. 9 is a side elevational view of the left side thereof;

FIG. 10 is a top plan view thereof; and,

FIG. 11 is a bottom plan view thereof.

The broken lines throughout show portions of a three wheel belt grinder that form no part of the claimed design.

The broken lines showing of a base in FIG. 1 is for the purpose of showing environmental structure, and forms no part of the claimed design.

1 Claim, 11 Drawing Sheets
